CHOCK

Filed Oct. 22, 1926

UNITED STATES PATENT OFFICE

ARTHUR ALFRED BUREAU, OF CHICAGO, ILLINOIS, ASSIGNOR TO WESTERN ELECTRIC COMPANY, INCORPORATED, OF NEW YORK, N. Y., A CORPORATION OF NEW YORK

CHOCK

Application filed October 22, 1926. Serial No. 143,342.

This invention relates to chocks for limiting the movement of objects during their transportation, and more particularly to stay blocks especially adapted for securing cable reels and similarly shaped articles in the cars in which they are transported.

An object of the invention is to provide a chock which is light in weight but which is sufficiently rigid to effectively prevent dis-
placement of the supported object.

The invention contemplates the provision of a chock for gradually overcoming the force of an impact, thereby greatly increasing its effectiveness. In accordance with one embodiment, the invention contemplates the provision of a chock whose supporting face comprises several sections disposed at progressively increasing angles to gradually overcome the force tending to displace the supported object.

It is believed that a better understanding of the invention may be had by reference to the following description, taken in conjunction with the accompanying drawing, in which

Fig. 1 is a side elevation of the chock;

Fig. 2 is a plan view of the device illustrated in Fig. 1, and

Fig. 3 is a perspective view showing the chock supporting a cable reel.

Referring to the drawing in which similar reference characters designate the same parts in the several views, the chock is designated generally by the numeral 6, which rests upon a base comprising a pair of base plates 7 and 8 connected by a brace 9. Extending upwardly from the base plates 7 and 8 are two arms 11 and 12, respectively, disposed at such an angle to the base plates as to be substantially perpendicular to the general slope of a supporting surface 13 which is carried by the arms. The supporting surface 13 of the chock comprises two inclined plane sections 14 and 15 and a curved section 16. The supported object which may be a cable reel 21 normally rests on the section 14 with which it makes a line contact, its position being indicated at 22 in Fig. 1. This section is made slightly wider than the remaining sections to afford the greatest supporting surface at

the point where the greatest shock will occur, thus preventing damage to the object supported. The upper sections are narrower since the object supported, if jarred out of the normal position, will have lost most of its momentum before contacting with these surfaces, hence the supporting surface provided for the object need not be of very great width. Section 14 is also disposed at such an angle to the supported object that if a forceful impact is imparted to the object it will tend to roll up the inclined plane instead of tearing the chock from its fastenings. This feature is based on the well known principle that the force exerted by a moving object is proportional to its mass times its acceleration. If, therefore, an object in motion were stopped instantaneously the force required to stop it would be infinite. In practice, a moving object is never stopped instantaneously. In the case of an ordinary chock whose supporting face conforms to the contour of the supported object, there will be a slight movement of the chock which will tend to loosen it from its fastenings. The chock of the present invention is constructed of a plurality of inclined planes and when the supported object has rolled up the first inclined section 14 its momentum will have been greatly decreased and it will then encounter the second inclined section 15 whose inclination is larger than that of the first section. It will be seen that due to the decreased momentum and increased slope the stopping force will remain substantially the same value. The contour of the curved section 16 corresponds substantially to the shape of the supported object so that when the object reaches this section as indicated by dot and dash line 23 in Fig. 1 its force will be largely spent and the movement of the object will be effectively arrested.

The base plates 7 and 8 are provided with a number of holes 17 to receive screws 18 by which the chock may be fastened to the floor. The holes in base plate 8 are arranged at an angle of 45 degrees to the floor in planes substantially parallel to the plane of the chock. The object of this arrangement is to prevent the screws from being withdrawn in a

straight line along their length when the chock tends to pivot about the base plate 7, thus lending them a greater securing effect.

It will be understood that the embodiment of the invention herein described and illustrated is merely a convenient and useful form of the invention which is capable of many other modifications without departing from the spirit and scope of the invention.

What is claimed is:

- 10 1. A device for supporting a cylindrical object comprising a base, a plurality of plane supporting surfaces with the uppermost of said surfaces normally out of contact with the object arranged at progressively increasing angles with the base, and means for supporting said surfaces on the base.
- 15 2. A device for supporting a cylindrical object comprising a base, a plurality of plane supporting surfaces arranged at progressively increasing angles with the base, a curved surface substantially of the contour of the supported object, and means for supporting said surfaces on the base.
- 20 3. A device for limiting the rolling movement of an object comprising a base, a supporting surface having upper and lower plane surfaces of such configuration as to make, normally on the lowest plane surface, a line contact with the supported object and having a progressively increasing slope, and means to support said surface on the base.
- 25 4. A device for limiting the rolling movement of an object comprising a base, a supporting surface having a plurality of sections at gradually increasing angles with the base, and means for supporting the surface on the base.
- 30 5. A device for supporting an object comprising a base, a plurality of plane supporting surfaces having different widths arranged at progressively increasing angles with the base, and means for supporting said surfaces on the base.
- 35 6. A device for limiting the rolling movement of an object, comprising a base, a plurality of plane supporting surfaces, the widest plane supporting surface at the normal line of contact with the object to be supported, a narrower plane supporting surface at a progressively increased angle to the base, a curved surface substantially of the contour of the object to be limited in movement, and means for supporting said surfaces on the base.
- 40 7. A device for supporting a cylindrical object comprising a plane supporting surface normally engaged by the article, a second plane surface disposed at an angle with the base different from that of the other supporting surface and normally out of engagement with the article to allow some movement of the article, and means for supporting said surfaces on the base.
- 45 8. A device for chocking a cylindrical ob-

ject comprising a base, a plurality of inclined plane supporting surfaces, the lowermost of said surfaces normally in contact with the object, the uppermost of said surfaces at a greater inclination than said first mentioned surface and extending away from the axis of the object supported, and means for supporting the surfaces on the base.

In witness whereof, I hereunto subscribe my name this ninth day of October, A. D. 1926.
